RAILWAY SIGNALING SYSTEM

Henry S. Young, Wilkinsburg, Pa., assignor to
The Union Switch & Signal Company, Swiss-
vale, Pa., a corporation of Pennsylvania

Application April 13, 1935, Serial No. 16,185
Renewed July 30, 1936

24 Claims. (Cl. 246—46)

The present invention relates in general to railway signaling systems, but more particularly to improvements in automatic block signaling systems. One feature of the invention has to do with the use of apparatus and circuits enabling advantage to be taken of an existing alternating current supply paralleling the railway, or available at the respective signal locations, in such a manner that "clear" control of the signals may be accomplished by employing alternating current, and "caution" control of the signals may be accomplished by employment of direct current. A further feature resides in the provision of means enabling both the "clear" and "caution" control to be exercised over a conductor common to all signals and but one other line wire extending between the signals of adjacent sections. There are also numerous other features not specifically mentioned, but which will appear from time to time during the progress of the specification.

The invention is illustrated in two sheets of drawings wherein, Fig. 1 diagrammatically illustrates the invention applied to the control of semaphore type signals arranged at the junctions of adjoining track sections of a stretch of railway track; Figs. 2 and 3 illustrate different manner in which the battery charging circuits forming a part of the signaling system may be varied; while Fig. 4 shows the invention applied to the control of color-light signals located at the junctions of adjoining track sections in the same manner as are the semaphore signals of Fig. 1.

The application of the invention as illustrated by Fig. 1 will first be described. The reference character E designates a railway track along which traffic normally moves in the direction indicated by the arrow. The rails of this track are divided by the usual insulated joints to form a series of track sections 6—7, 7—8, etc. Each section is provided with a track circuit comprising a battery 10 connected across the rails at the exit end and a track relay T connected across the rails at the entrance end thereof.

Each section is provided with a three position semaphore signal, a pair of direct current signal control relays H and D for the associated signal, and an alternating current relay K. The relay H is of the slow acting type and when energized completes a circuit for moving the associated semaphore signal to "caution" position. The relay D is arranged to operate by direct current received from a bridged rectifier R when such rectifier is fed alternating current via the secondary winding of a transformer X. The pri-

mary winding of the transformer X normally receives alternating current from the secondary S3 of a transformer W at the next signal location in advance. For example, the primary winding of transformer IX receives current from the secondary winding S3 of transformer 3W. This circuit first extends through the signal contact 3A, the winding of alternating current relay 3K and back to the other side of winding S3 via the common conductor. The relay 3K picks up over this circuit and at its front contact and armature 18 then extends the connection of one terminal of the secondary S3 to the conductor 6L, through front contacts of track relay 6T, resistor 1Z, the primary winding of transformer IX, conductor 2, and thence back to the other terminal of the secondary S3 via the common conductor. The D or "clear" relay of a signal, when energized, completes a circuit through the signal to hold it in its "clear" position. For example, with relay 1D energized the signal 1 is held in its clear position by circuits completed by front contacts 11, 12, and 13 of relay 1D. These circuits extend from the plus side of battery C1 through front contacts 11 and 12 to "caution" and "clear" operating conductors 15 and 16 extending to signal 1, and from the minus terminal of battery C1, over the common conductor and conductor 2, through front contacts 13 of relay 1D to conductor 17 extending to signal 1.

The same line conductors over which the primary winding of a transformer X is supplied with alternating current to effect energization of the "clear" or D relay of a signal are also employed as a part of the circuit of the H or "caution" relay of a signal. For example, the energizing circuit of relay 1H extends from the plus terminal of battery C2, the back contact and armature 18 of relay 3K, line conductor 6L, front contacts of relay 6T, the winding of relay 1H, back contact 14 of relay 1D and back over conductor 2 and the common conductor to the minus side of battery C2. It will be observed that part of the current flowing over conductor 6L also passes via resistor 1Z and the primary winding of the transformer IX. The resistor 1Z is provided in this latter circuit to prevent too much current being shunted from relay 1H. When the H relay of a signal is energized its contacts 21 and 22 close a circuit for moving the associated signal to its "caution" position. For example, if relay 1H is picked up, the "caution" circuit of signal 1 is completed. This circuit extends from the plus side of battery C1, through the front contact and armature 22 of relay 1H, "caution" conductor 15

to the signal 1 and from the minus side of battery C1, the common conductor, conductor 17^a, and the front contact 21 of relay 1H to the conductor 17 extending to signal 1.

5 Since the L conductor of a section includes front contacts of the track relay of the associated section the operating current for both relays D and H of a section is interrupted whenever the section is occupied. When both the D and H relays of a 10 signal are deenergized the signal will be in its "stop" position and will, at its A contacts open the circuit of the associated K relay.

At each signal location a secondary S2 of the 15 associated transformer W feeds alternating current to a bridged rectifier BR which in turn feeds direct current through a resistor Y at the proper voltage to maintain the associated battery C properly charged. The lamp employed in the 20 semaphore signal is continuously energized by alternating current supplied to it via a secondary S1 of transformer W.

As shown in the drawings, all sections of the stretch are unoccupied, and at least two sections in advance of section 8-9 are assumed to be also 25 unoccupied; accordingly, all track relays T and all D relays are energized, and all signals are in their "clear" position.

It will now be assumed that a train enters section 6-7 and that accordingly the track relay 30 6T of this section becomes deenergized. With the contacts of track relay 6T open, the line conductor 6L is interrupted and relay 1D becomes deenergized. The relay 1D on releasing, at back contact 14 prepares an operating circuit for relay 1H and at front contacts 11 and 12 disconnects the plus terminal of battery C1 from the "caution" and "clear" operating conductors 15 and 16 of the associated signal 1. The signal 1 accordingly moves to its "stop" position in the usual 35 manner. The relay 1D also, at the front contact of its armature 13, disconnects the conductor 17 from the branch conductor 2 of the common conductor and accordingly from the minus terminal of battery C1, and at its back contact closes a 40 shunt about the "caution" operating circuit of signal 1. This shunt path extends from the back contact of armature 13 through the back contact and armature 22 of relay 1H to the "caution" conductor 15 of signal 1, and from the armature 13 45 of relay 1D to the conductor 17 of the signal. Since in this type of signal it is necessary for the "caution" circuit to be energized to move the signal to "clear" position, it will be evident that the traced shunt path fully guards the signal against 50 its being falsely cleared while relays 1H and 1D are both deenergized. When the signal 1 returns to its "stop" position its contact 1A opens and therefore disconnects the alternating current from relay 1K and from the line conductor 5L. 55 The relay 1K accordingly releases its armature 18, which, at its back contact connects the plus side of battery C1 to the line conductor 5L. When the train clears the section preceding 6-7 the battery potential applied to conductor 5L becomes 60 effective to energize the H relay at the preceding signal location to control the movement of the signal of the preceding section from its "stop" to its "caution" position.

When the train enters section 7-8 track relay 70 7T releases and interrupts the feed circuit for relay 3D. When relay 3D releases, it interrupts points in the "clear" and "caution" circuits of signal 3 and places a shunt about its "caution" operating circuit in the same manner as the corresponding relay 1D of section 6-7 controls sig-

nal 1. When signal 3 returns to its "stop" position, its contact 3A opens the circuit of relay 3K, which accordingly also releases.

As soon as the train clears section 6-7, the track relay 6T again picks up and, with relay 3K in its release position, completes the operating circuit of relay 1H. Relay 1H now picks up and completes the "caution" operating circuit of signal 1.

When signal 1 reaches its "caution" position its contact 1A recloses the circuit of relay 1K. The relay 1K accordingly picks up its armature 18, thereby disconnecting the plus side of battery C1 from the conductor 5L and reconnecting alternating current thereto to release its H relay and pick up its D relay to control the movement of the signal of the preceding section from its "caution" to its "clear" position.

When the train enters section 8-9 the track relay 8T releases and interrupts the feed circuit of relay 5D. When relay 5D releases it interrupts points in the "clear" and "caution" circuits of signal 5 to effect its return to "stop" position and places a shunt about its "caution" operating circuit in the same manner as the corresponding relays 1D and 3D controlled their signals.

The signal 5, in returning to its "stop" position at its contact 5A interrupts the alternating current supply to relay 5K and line conductor 7L and accordingly relay 3D also becomes deenergized. When the relay 5K releases, the front contact of armature 18 opens a second point in the alternating current path to line conductor 7L and at its back contact connects the conductor 7L to the plus side of battery C3.

As soon as the train clears section 7-8, the track relay 7T again picks up and, with relay 5K in its released position, completes the operating circuit of relay 3H. Relay 3H now picks up and completes the "caution" operating circuit of its signal 3. When signal 3 reaches its "caution" position its contact 3A recloses the circuit of relay 3K. The relay 3K accordingly picks up its armature 18, thereby opening the energizing circuit of relay 1H by disconnecting the plus side of battery C2 from the conductor 6L and reclosing the alternating current circuit through the primary winding of transformer 1X to effect the reenergization of relay 1D. It may be well to mention at this time that, owing to the slow release characteristic of relay 1H it holds the "caution" circuit of its signal closed until relay 1D has had time to pick up and close the "clear" circuit of the signal, so as to prevent the signal from starting to move toward its "stop" position when changing from its "caution" to its "clear" position.

In case a train enters a section and then recedes out of it, it will be seen that alternating current will be applied to the L conductor to pick up the D relay of such section, while the associated H relay is in its release position. Owing to the construction of the H relay, it has a high impedance to alternating current and therefore will not pick up on the alternating current voltage applied. The circuit of the H relay is, however, opened at the back contact 14 of the D relay and so prevents operation of the H relay should it, through faulty adjustment, have a tendency to do so. The opening of the back contact 14 also serves to save such alternating current power as might otherwise flow through the H relay when alternating current is being applied to clear the signal.

When the train clears section 8-9, a circuit

such as traced for relay **1H** will immediately be completed through the relay **5H** and the signal **5** will accordingly be moved from its "stop" to its "caution" position.

- 5 In Fig. 1 it will be observed that the batteries at the respective signal locations are under continuous charge. With this arrangement if a battery charging rectifier **BR** becomes short-circuited the alternating current of the secondary 10 **10** **S2** of the transformer **W** will flow out over the **L** conductor when the associated signal is at "stop" at the same time that the plus terminal of the associated battery is connected to the conductor **L** to operate the **H** relay. The alternating 15 **15** current voltage of the secondary **S2** is insufficient to operate the **D** relay, however, and therefore no false operation of a signal will result from failure of a battery charging rectifier.

In Fig. 2 the battery charging circuit is illustrated as passing through front contact **19** of the **K** relay. With the battery charging circuits modified in this manner, charging of the battery occurs only while the associated signal is in its "clear" or "caution" position, and therefore while the battery itself is disconnected from the associated **L** conductor. There is accordingly no opportunity with this arrangement of feeding alternating current from the secondary **S2** to the **L** conductor.

- 30 In Fig. 3 is shown a still further manner in which danger of alternating current from the transformer winding **S2** reaching the **L** conductor may be avoided. In this illustration the battery charging circuit includes front contact **D15** 35 of the **D** relay, closed only when the associated signal is at "clear", and the **B** contact of the associated signal closed only when the signal is in its "clear" or "caution" position; or alternatively, contacts **H23** of relay **H**, closed only 40 when the associated signal is at "caution" and the **B** contacts of the signal is in its "clear" or "caution" position. As in the former arrangement, alternating current from winding **S2** cannot, with this arrangement, reach the battery 45 while the battery is connected to the **L** conductor, and charging will only occur while the signal is in the "clear" or "caution" position.

In case of temporary failure of the alternating current supply the **K** and **D** relays will obviously become deenergized. The **K** relays will, however, complete the usual operating circuits of the **H** relays and accordingly the signals which were formerly displaying a "clear" indication will now display a "caution" indication. 55 The track relays will function in the usual manner to open the line circuits as their respective sections are occupied and accordingly the signals of occupied sections will return to "stop" in the normal manner.

- 60 In applying the invention to an automatic block signaling system employing color-light signals, as has been done in Fig. 4, the circuits are quite similar to those already described and therefore the description of the latter application need be only briefly gone into. In the illustration of Fig. 4, as in Fig. 1, all sections of the stretch and two or more sections in advance of sections **36**—**37** are assumed to be unoccupied and therefore all signals are displaying a "clear" indication. The **H** and **D** relays of the color-light system are controlled in identically the same manner as when employed in a system employing semaphore signals. The actual operating circuit of the **H** relay of the color-light system, however, is slightly different than that employed in the semaphore system. In

the color-light system the operating circuit of each **H** relay includes the winding of the **K** relay associated with the next signal in advance. The windings of the **K** relays are of low resistance but of high impedance so that they offer very little 5 **5** resistance to the flow of the direct current employed in operating the **H** relays. The circuit for an **H** relay of the color-light system, **43H**, for example, extends from the plus terminal of battery **C6**, through the back contact and armature **48** of relay **45K**, over line conductor **35L**, through the front contact of track relay **35T**, the winding of relay **43H**, back contact **49** of relay **43D**, conductor **52**, the common conductor, conductor **54**, and through the winding of alternating current relay **45K** and conductor **55** to the minus terminal of the battery **C6**.

Since the color-light signals have no contacts the **K** relays are operated through contacts of their associated **H** or **D** relay. Referring to the relay **43K**, for example, its operating circuit while relay **43D** is energized, extends from the left terminal of secondary **S5** of transformer **4W** over the common conductor, conductor **54**, through the winding of relay **43K**, conductor **55** and through front contact **46** of relay **43D** to the right terminal of the secondary winding **S5**; or alternatively via the front contact **40** of relay **43H** when the latter relay is the one energized; and is deenergized whenever both relays **43H** and **43D** are deenergized. The armature **48** of relay **43K** corresponds to the armature **18** of the **K** relays employed in the system shown in Fig. 1 and in like manner feeds alternating or direct current to its 30 associated line conductor **34L**.

In the color-light system the "clear" and "caution" lamps of the signals, identified in the drawings as the "G" and "Y" lamps of the signals, are arranged to receive their operating current from the associated alternating current source; while the "stop" lamps, identified in the drawings as the "R" lamps of the signals, are arranged to receive their operating current from the associated battery. For example, the "G" lamp of signal **43** is energized by alternating current supplied by the secondary winding **S6** of the transformer **4W**, over a circuit extending from the right terminal of winding **S6**, through conductor **55**, the lamp **G**, the front contact and armature **47** of relay **43D**, the back contact and armature **42** of relay **43H**, and armature **44** and front contact of relay **43K** to the left terminal of the secondary winding **S6**.

With relay **43H** energized, in lieu of **43D**, the "Y" lamp is energized by current supplied to it by the secondary winding **S6** via the front contact and armature **44** of relay **43K**, the armature **42** and front contact of relay **43H**, the lamp **Y** and over the previously traced circuit to the other terminal of the secondary winding **S6**.

If the section **35**—**36** is occupied, both relays **43H** and **43D** are in the released position and accordingly the relay **43K** is also in the released position. Under these circumstances a circuit for the "R" lamp of the signal is completed. This circuit extends from the plus terminal of battery **C5**, through the back contact and armature **44** of relay **43K**, armature **42** and back contact of relay **43H**, armature **47** and back contact of relay **43D**, the **R** lamp, and over conductor **55** to the minus terminal of battery **C5**.

In the color-light system the slow release characteristic of the **H** relays prevents momentary completion of the "R" lamp circuit of a signal when the indicating condition of the signal is being changed from "caution" to "clear", by hold-

ing the "Y" lamp circuit closed until the D relay has had time to pick up and establish the circuit of the "G" lamp of the signal.

In the color-light system, in case of failure of the alternating current supply, the K and D relays become deenergized as they do in the semaphore system. The "G" lamps of the signals which before such failure were lighted to display a "clear" indication, are accordingly retired. The 10 K relays of such signals on releasing, however, now complete the customary energizing circuits for the H relays under their control and accordingly the H relays become energized in the usual manner. With the H relay of a signal location 15 energized and the K relay of the same location deenergized, a direct current operating circuit is established for the "Y" lamp of the associated signal. For example, with the relay 43H energized and the relay 43K in the released position, a circuit is completed for the "Y" lamp of the associated signal 43. This circuit extends from the plus terminal of battery C5, through the back contact and armature 44 of relay 43K, armature 42 and front contact of relay 43H, through the "Y" 20 lamp of the signal to conductor 55 and to the minus terminal of the battery C5. It will, therefore, be seen that in applying the invention to the control of color-light signals, as in the application of the invention to the control of semaphore signals, the failure of the alternating current supply will cause the signals to display "caution" and "stop" indications in accordance with traffic conditions.

Although the invention as described herein has 35 only been applied to automatic block signaling systems employing semaphore and color-light signals, it will be understood that various changes and modifications may be made to apply the same to signaling systems employing other types 40 of signals without departing from the spirit and scope of the invention.

Having thus described the invention, what I claim is:

1. In combination, a railway track divided into 45 sections, three relays D, H and K for each section at the entrance thereof, a line circuit extending between adjacent sections and over which either relay D or H of the rear section may be operated, means for supplying said line circuit from the 50 forward of said sections with current suitable for operating one or the other of such relays D or H depending upon the energized or deenergized condition of the relay K of the forward section, track circuits for said sections including track relays 55 having contacts for effecting the deenergization of the D and H relays of their associated section when such section becomes occupied, traffic controlling means at each relay location directly controlled by the D and H relays at such location, and a circuit for the K relay at such location controlled exclusively by the traffic controlling means 60 at such location.

2. In combination, a railway track divided into 65 sections, three relays D, H and K for each section at the entrance thereof, a line circuit extending between adjacent sections and over which either relay D or H of the rear section may be operated, means for supplying said line circuit from the 70 forward of said sections with current suitable for operating one or the other of such relays D or H depending upon the energized or deenergized condition of the relay K of the forward section, track circuits for said sections including track relays having contacts for effecting the de- 75 energization of the D and H relays of their asso-

ciated section when such section becomes occupied, traffic controlling means at each relay location controlled by the D and H relays at such location, and a circuit for the K relay at such location controlled by the traffic controlling means at such location.

3. In combination, a railway track divided into sections, three relays D, H and K for each section at the entrance thereof, a line circuit extending between adjacent sections and over which either relay D or H of the rear section may be operated, means for supplying said line circuit from the forward of said sections with current suitable for operating one or the other of such relays D or H depending upon the energized or deenergized 10 condition of the relay K of the forward section, track circuits for said sections including track relays having contacts for effecting the deenergization of the D and H relays of their associated sections when such section becomes occupied, traffic controlling means at each relay location controlled by the D and H relays at such location, and a circuit for the K relay at such location controlled by the associated D and H 15 relays.

4. In combination, a railway track divided into sections, three relays D, H and K for each section at the entrance thereof, a line circuit extending between adjacent sections and over which either relay D or H of the rear section may be operated, means for supplying said line circuit from the forward of said sections with current suitable for operating one or the other of such relays D or H depending upon the energized or deenergized 20 condition of the relay K of the forward section, track circuits for said sections including track relays having contacts for effecting the deenergization of the D and H relays of their associated sections when such section becomes occupied, traffic controlling means at each relay location controlled by the D and H relays at such location, and a circuit for the K relay at such location controlled by the associated D and H 25 relays.

5. In combination, a railway track divided into sections, three relays D, H and K for each section at the entrance thereof, a line circuit extending between adjacent sections and over which either relay D or H of the rear section may be operated, means for supplying said line circuit from the forward of said sections with current suitable for operating one or the other of such relays D or H depending upon the energized or deenergized 30 condition of the relay K of the forward section, track circuits for said sections including track relays having contacts for effecting the deenergization of the D and H relays of their associated section when such section becomes occupied, traffic controlling means at each relay location controlled by the D and H relays at such location, and a circuit for the K relay at such location closed when either of the associated D or H relays 35 is energized.

5. In combination, a railway track divided into 45 sections, three relays D, H and K for each section at the entrance thereof, a line circuit extending between adjacent sections and over which either relay D or H of the rear section may be operated, means for supplying said line circuit from the forward of said sections with current suitable for operating one or the other of such relays D or H depending upon the energized or deenergized 50 condition of the relay K of the forward section, track circuits for said sections each including a track relay having a contact for effecting the deenergization of the D and H relays of its associated section when such section becomes occupied, traffic controlling means at each relay location controlled by the D and H relays at such location, and a circuit for the K relay at such location including front contacts of either 55 of the associated D and H relays which happens to be energized.

6. In combination, a railway track divided into sections, three relays D, H and K for each section at the entrance thereof, a line circuit extending between adjacent sections and over which either relay D or H of the rear section may be operated, means for supplying said line circuit 60 from the forward of said sections with current suitable for operating one or the other of such relays D or H depending upon the energized or deenergized condition of the relay K of the forward section, track circuits for said sections including front contacts of either 65 of the associated D and H relays which happens to be energized.

cluding track relays having contacts for effecting the deenergization of the D and H relays of their associated sections when such sections become occupied, traffic controlling means at each relay 5 location controlled by the D and H relays at such location, and a circuit for the K relay at such location jointly controlled by the track relay of the section immediately in advance of the associated traffic controlling means and one of the two 10 associated D or H relays.

7. In combination, a railway track divided into sections, two direct current neutral relays H and D and an alternating current relay K for each section, a line circuit for each two adjacent sections 15 including the H relay of the rear section and the primary winding of a transformer-rectifier coupling between the line and the D relay of the rear section, means for supplying each of said circuits with alternating or direct current to 20 selectively energize said D or H relays according as relay K of the forward section is energized or deenergized, track circuits for the sections including track relays for the control of said line circuits, and traffic governing means for the sections 25 controlled by said D and H relays.

8. In combination, a railway track divided into sections, two direct current neutral relays H and D and an alternating current relay K for each section, a line circuit for each two adjacent sections 30 including the H relay of the rear section and the primary winding of a transformer-rectifier coupling between the line and the D relay of the rear section, means for supplying each of said circuits with alternating or direct current to 35 selectively energize said D or H relays according as relay K of the forward section is energized or deenergized, track circuits for the sections including line circuits, traffic governing means having operating circuits selectively closed by said D and H 40 relays, and means for placing a shunt about one of such operating circuits when both of said relays are deenergized.

9. In combination, a railway track divided into sections, three relays D, H and K for each section, a line circuit for each two adjacent sections 45 over which either relay D or H of the rear section may be operated, means for supplying each of said circuits with current of one character or another according as the K relay of the forward section is energized or deenergized to selectively 50 energize one or the other of such D or H relays, means operating when any one section is occupied by a train to open the line circuit, traffic governing means controlled by the D and H 55 relays, and operating circuits for the K relays controlled by the traffic governing means.

10. In combination, a railway track divided into sections, three relays D, H and K for each section, a line circuit for each two adjacent sections 60 over which either relay D or H of the rear section may be operated, an alternating current source and a storage battery for supplying each of said circuits with alternating or direct current to selectively energize one or the other of said D or H 65 relays according as the K relay of the forward section is energized or deenergized, means operating when any one section is occupied by a train to open the line circuit, traffic governing means controlled by the D and H relays, operating 70 circuits for the K relays controlled by the traffic governing means, and means for charging the battery from the alternating current source while the associated K relay is energized.

11. In combination, a railway track divided 75 into sections, three relays D, H and K for each

section, a line circuit for each two adjacent sections over which either relay D or H of the rear section may be operated, an alternating current source and a storage battery for supplying each of said circuits with alternating or direct current to selectively energize one or the other of said D or H 10 relays according as the K relay of the forward section is energized or deenergized, means operating when any one section is occupied by a train to open the line circuit, traffic governing means controlled by the D and H relays, operating circuits for the K relays controlled by the traffic governing means, and means for charging the battery from the alternating current source through front contacts of one of the associated D or H relays. 15

12. In combination, a railway track divided into sections, three relays D, H and K for each section, a line circuit for each two adjacent sections over which either relay D or H of the rear section 20 may be operated, an alternating current source and a storage battery for supplying each of said circuits with alternating or direct current to selectively energize one or the other of said D or H relays according as the K relay of the forward 25 section is energized or deenergized, means operating when any one section is occupied by a train to open the line circuit, traffic governing means controlled by the D and H relays, operating circuits for the K relays controlled by the traffic 30 governing means, and means for charging the battery from the alternating current source only while the associated signal is giving a proceed indication. 35

13. In combination, a railway track divided into sections, three relays D, H and K for each section, a line circuit for each two adjacent sections over which either relay D or H of the rear section may be operated, an alternating current source and a storage battery for supplying each of said circuits with alternating or direct current to selectively 40 energize one or the other of said D or H relays according as the K relay of the forward section is energized or deenergized, means operating when any one section is occupied by a train to open 45 the line circuit, traffic governing means controlled by the D and H relays, operating circuits for the K relays controlled by the traffic governing means, and means for charging the battery from the alternating current source only while alternating 50 current is being supplied to the associated line circuit. 55

14. In combination with a stretch of track divided up into track sections, a block signaling system with signals at the junctions of the respective sections, a pair of relays D and H at the junction of adjoining sections for controlling the associated signal in accordance with traffic conditions, a K relay associated with the D and H relays, sources of alternating and direct current 60 adjacent each signal, line circuits extending between the sources of current at a signal and the D and H relays of the next signal to the rear, normally closed energizing circuits for the K relays of the respective sections, an energizing circuit 65 for the D relay of each signal closed over the line circuit by the energized K relay of the signal in advance of it; a circuit for operation of the signal associated with such D relay to its clear indicating position, and including the associated direct current source; traffic controlled means effective when a section is occupied to interrupt the associated line circuit and thereby effect the deenergization of the D relay at the entrance of the occupied section to enable the associated signal to 70 75

change from its clear to its stop indicating position, means controlled by such signal in moving to its stop position to interrupt the circuit of the associated K relay, and means controlled by such 5 K relay for substituting the associated direct current source for the alternating current source to effect the energization of the H relay of the next signal to the rear and the deenergization of the D relay thereat, and a circuit closed by energization 10 of such H relay for moving the latter signal to its caution position.

15. In combination with a stretch of railway track divided up into track sections each equipped with the usual track circuit including a track relay, and also equipped with successive signal locations each having a signal capable of displaying clear, caution or stop; a pair of neutral relays at 15 each signal location for controlling the associated signal in a manner depending on which relay of the pair is energized or on the deenergized condition 20 of both relays of the pair, means enabling the selective energization of either of said relays over a circuit comprising of but two conductors extending between the associated signal location 25 and the next signal location in advance, and a contact of a track relay of a section intervening two signal locations included in one of such conductors.

16. In combination with a stretch of railway 30 track divided up into track sections each equipped with the usual track circuit including a track relay, and also equipped with successive signal locations each having a signal capable of displaying clear, caution or stop; a pair of neutral 35 direct current relays at each signal location for controlling the associated signal in accordance with traffic conditions in advance, means enabling the energization of one of said relays to the exclusion of the other from the signal location 40 in advance over a two conductor circuit extending between such signals and including a source of direct current at the advance signal location, means including the same two conductors and a source of alternating current enabling 45 the energization of the other relay to the exclusion of the first relay, and a contact of one of the track relays in a section of the track intervening such signal locations insuring the deenergization of both relays in case such section is 50 occupied.

17. In combination, a forward section and a rear section of railway track, a line circuit for the rear section, a signal controlled by said line circuit and arranged to display a less restrictive 55 proceed aspect when said line circuit is supplied with alternating current or a more restrictive proceed aspect when said line circuit is supplied with direct current, a source of alternating current, a source of direct current, means including said two sources of current for supplying said line circuit with alternating current when the forward section is unoccupied provided the alternating current is then available and for supplying said line circuit with direct current 60 energy from said direct current source when the forward section is occupied or when the alternating current energy is absent.

18. In combination, a forward section and a rear section of railway track, a line circuit for 70 the rear section, a signal controlled by said line circuit and arranged to display a less restrictive proceed aspect when said line circuit is supplied with alternating current or a more restrictive proceed aspect when said line circuit is supplied 75 with direct current, a source of alternating cur-

rent, a source of direct current, a relay which is energized when the forward section is unoccupied provided the alternating current source is then available and which is deenergized when the forward section is occupied or when the alternating current is absent, and contacts of said relay for connecting said line circuit with said alternating current source when said relay is energized and for connecting said line circuit with said direct current source when said relay is deenergized. 10

19. In combination, a section of railway track, a circuit for said section, a signal controlled by said circuit and arranged to display a normal proceed aspect or a more restrictive proceed aspect according as said circuit is supplied with alternating current or with direct current respectively, a source of direct current, a source of alternating current, and means for connecting said circuit with said direct current source or with 15 said alternating current source in accordance with traffic conditions in advance of said section and for connecting said circuit with said direct current source when said alternating current source is absent regardless of traffic conditions 20 in advance. 25

20. In combination, a forward and a rear section of railway track, a pair of conductors for the rear section controlled by traffic conditions in that section, a source of energy of one character and a source of energy of another character, means effective when the forward section is unoccupied to connect said pair of conductors with the source of energy of said one character, means effective when the forward section is occupied as well as when the source of energy of said one character is not available to connect said pair of conductors with the source of energy of said other character, and signaling means for the rear section governed by said pair 30 of conductors and selectively responsive to the character of current with which such conductors are supplied. 35

21. In combination, a forward and a rear section of railway track, a source of energy of one character and a source of energy of another character, a pair of conductors for the rear section controlled by traffic conditions in that section, and means for connecting said pair of conductors with the source of energy of said one character or with the source of energy of said other character in accordance with traffic conditions in said forward section, said means being automatically effective to connect said pair of conductors with the source of energy of said one character when the source of energy of said other character is not available regardless of traffic 40 conditions in said forward section. 50

22. In combination, a forward and a rear section of railway track, a source of energy of one character and a source of energy of another character, a pair of conductors for the rear section controlled by traffic conditions in that section, means for connecting said pair of conductors with the source of energy of said one character or with the source of energy of said other character in accordance with traffic conditions in said forward section, said means being automatically effective to connect said pair of conductors with the source of energy of said one character when the source of energy of said other character is not available regardless of traffic 60 conditions in said forward section, and traffic governing apparatus for the rear section controlled by said pair of conductors. 65

23. In combination, a forward and a rear section of railway track, a source of energy of one character and a source of energy of another character, a pair of conductors for the rear section controlled by traffic conditions in that section, means for connecting said pair of conductors with the source of energy of said one character or with the source of energy of said other character in accordance with traffic conditions 5 in said forward section, said means being automatically effective to connect said pair of conductors with the source of energy of said one character when the source of energy of said other character is not available regardless of traffic 10 conditions in said forward section, and a signal for the rear section controlled by said pair of conductors, said signal capable of displaying a more restrictive proceed aspect or a less restrictive proceed aspect according as said pair of 15

conductors is supplied with energy of said one character or with energy of said other character respectively.

24. In combination, a section of railway track, a pair of conductors controlled by traffic conditions in said section, a source of energy of one character and a source of energy of another character, and means for supplying said pair of conductors with energy from the source of said one character or with energy from the source of 5 said other character in accordance with traffic conditions in advance of said section, said means being effective to supply said pair of conductors with energy from the source of said one character when the source of energy of said other character is absent regardless of traffic conditions in 10 advance of said section. 15
